UNITED STATES PATENT OFFICE

WILLIAM SHILOH WILSON, OF WASHINGTON, DISTRICT OF COLUMBIA, ASSIGNOR OF FIFTY PER CENT TO SHERMAN W. FRAZIER, OF WASHINGTON, DISTRICT OF COLUMBIA

ADVERTISING APPARATUS

Application filed March 28, 1929. Serial No. 350,556.

The present invention relates to improvements in advertising apparatus, one object of the invention being the provision of a machine of the type shown and described in my 5 co-pending application filed February 9th, 1929, Serial No. 338,738, except that in the present machine a script type sign carrying member may be attached to the rotary sign carrying member as a cylinder, and carry the 10 various independent display signs, one to each partition of the member, or four signs may be used separately as in the above mentioned application.

Another object of the present invention is 15 the provision of an advertising apparatus in which the electrical lighting system may be selectively controlled to give an intermittent lighting as in said pending case and also a steady lighting while the sign carrying member or members is or are intermittently and slow motion rotated.

Still another object of the present invention is the provision of a gearing arrangement between the motor and master driven 25 rotary sign, whereby at will the sign carrying member may be given a rotary slow motion movement or an intermittent rotation, thus providing an advertising apparatus for point of sale advertising with all of the best 30 selling features embodied in a single machine.

In the accompanying drawings:—

Figure 1 is a front elevation of a complete triple exhibiting advertising apparatus embodying the present invention.

Figure 2 is a longitudinal section through the two lower sign carrying members and the casing supporting the same.

Figure 3 is a cross section through one end 40 of the lower or master carrying sign member showing the gearing.

Figure 4 is a section on line 4—4 of Figure 3.

Figure 5 is a cross section through a sign carrying member showing a script sign in place.

Figure 6 is a perspective view on a very small scale of one of the script signs per se.

Figure 7 is an enlarged detail sectional view showing one form of mechanism 50 whereby the sign carrying member has se-

lectively continuous or intermittent movement imparted thereto.

Figure 8 is a section taken on line 8—8 of Figure 7.

Referring to the drawings, the numeral 7 55 designates a base, which has mounted thereon a casing 8, provided with three openings 9, through the sides as will presently appear. This casing here shown as a single casing, can, however, be made in a sectional 60 manner as set forth in my copending application.

An electric motor 10 is the prime mover for the present apparatus, and its shaft 11 drives the short shaft 12, as clearly shown 65 in figure 7. Slidably mounted upon the outer end of the shaft 12 and rotatable therewith through the pin-and-slot connection 13' is a sleeve 13, and pinned to the outer end of the sleeve 13 and movable therewith is a shaft 70 12', which has mounted fixedly thereon the gear 16 and the star gear 19 of a Geneva movement. A pin 19' attaches the star gear 19 to the sleeve 13'. Formed integrally with the sleeve 13 are two grooves 13'' and 13''', the 75 former to receive the upper end of the shifting lever 14, which in turn is manually operated by the push and pull rod 15 to shift the sleeve 13 as will presently appear. Connected to one end of a sign carrying member 80 22 is a driven shaft 21, whose other end is journalled in the bearing 22', and fixed to this shaft is one member 20^a of a clutch by means of a pin 20^c, while slidably mounted on the shaft 21 are two metal tubular members 20', and 20'', the former having a radius member or arm 13^a, whose free end encircles the sleeve 13 in the groove 13''', so that as the sleeve 13 is moved, the members 20' and 20'' are also moved, and the clutch member 20^a is moved into and out of engagement with the member 20^c. The star wheel 20 is geared to and rotates at all times 85 with the gear 19, and this wheel 20 is rotatable with the tubular member 20''. It 90 will thus be seen that as the lever 14 is operated, that is, when it is pushed to the right as viewed in Figure 7, the sleeve 13 and the tubular members 20' and 20'', are moved to the right also, thus placing the gear 16 into 95 100

Figure 1 is a front elevation of a complete triple exhibiting advertising apparatus embodying the present invention.

Figure 2 is a longitudinal section through the two lower sign carrying members and the casing supporting the same.

Figure 3 is a cross section through one end of the lower or master carrying sign member showing the gearing.

Figure 4 is a section on line 4—4 of Figure 3.

Figure 5 is a cross section through a sign carrying member showing a script sign in place.

Figure 6 is a perspective view on a very small scale of one of the script signs per se.

Figure 7 is an enlarged detail sectional view showing one form of mechanism whereby the sign carrying member has se-

mesh with the teeth 17 of the gear 18, of the sign carrying member 22 to cause the latter member to be rotated at a steady continuous speed, the star wheel having been 5 moved out of the path of the movable member 35 of the switch, to permit the switch to close and thus cause lamps to be energized during the continuous rotation of the sign carrying member. At the time that the 10 sleeve 13 was moved to the right, the clutch was thrown out and shaft 21 was free to rotate with the sign carrying member 22. To cause the sign carrying member to be rotated intermittently and also to cause the 15 switch to be intermittently opened and permitted to be closed, the rod 15 is pulled to the extreme left, thus releasing gear 16 from gear 18, and throwing in the clutch, so that the sign carrying member is driven from 20 sleeve 13 and the Geneva movement intermittently. Inasmuch as the star wheel 20 is now placed in the path to engage the switch member 35, the switch will now be intermittently opened and closed.

25 Each sign carrying member has two end members 23 and 24, and the correcting rails 25, four in number and constructed with the grooves 26 and 27. The member 24 surrounds the fixed shaft 28, which is a support 30 for the lamp 29, and the other member has attached thereto the shaft 21 and large gear 18, the external teeth 30 of which are in mesh with the small gear 31, mounted in the casing and engaging the large gear 32 of the 35 upper sign carrying member 33, and this latter member acts to drive the ones above, in this instance the member 34.

In order to control the lighting of the 40 lamps 29 and 29', a normally closed switch 35 is in the path to be intermittently opened and closed when the star wheel is being intermittently operated, and the sliding sleeve 13 is retracted, while when the sleeve is pushed inwardly to engage the gears 16 and 45 17, the switch is always closed. By this arrangement, the lamps are intermittently energized as the sign carrying members are intermittently operated and are continuously lighted when the members are being slowly 50 rotated.

The sign carrying members may be employed selectively to carry the single signs 36, 55 four to each member, with the glass protecting panel 37 interposed, or the script sign sheet 38 may be employed one to each member. When this is down the bent edge 39 is inserted in the slot or groove 27, and the sheet formed in a cylinder about the complete member using the rails 25 as the form, and the 60 free edge 40 which is mucilaged is moistened and engages as the overlap to secure the sign in encircling position. As this script sign is preferably made of a translucent paper, it can be made cheaply and when used torn off 65 and thrown away.

From the foregoing description, it is evident that with an advertising apparatus constructed according to and embodying this invention, that the various sign carrying members may be selectively acted upon by the motor to be continuously or intermittently rotated, that a script sign can be used with each member, or a plural number of panel signs as in my copending application can be used, and that the casing can be built-up or a single 70 unit, with the master sign carrying or lower member the driving member.

What is claimed, is:—

1. A display apparatus, including a casing, a plurality of rotary sign carrying members mounted therein, a motor to drive said members, two transmission mechanisms interposed between the motor and one of the sign carrying members, one mechanism to impart intermittent and the other to transmit continuous motion to the sign carrying members, and manually selective means for bringing into operation either of said mechanisms at a time. 80

2. A display apparatus according to claim 1, in which electric lamps are employed to illuminate said sign carrying members, and a switch under the control of the manually selective means whereby said switch is controlled thereby to cause the lamps to be intermittently or continuously energized as the sign carrying members are rotated. 95

3. A display apparatus, including a casing, a rotary sign carrying member mounted therein, an electric lamp mounted therein to illuminate the member, and a script sign sheet to be made in cylindrical form removably mounted upon and carried by said member, said sign carrying member having a plurality of spaced and grooved connecting members, the script sign sheet having a bent edge to fit in the groove of one connecting member while the sheet surrounds the other connecting members and has its free edge attached to the sheet adjacent the bent edge 100 thereof. 105

4. A display apparatus, including a base, a casing having a sign exhibiting opening, an electric motor, a rotary sign carrying member mounted in the casing, a shaft supporting one end of said member, a clutch member carried by said shaft, a sleeve slidably mounted and free to rotate on said shaft, a mating clutch member carried by the sleeve and when mated with the other clutch member rotates with the shaft, a star wheel carried by the sleeve, a driving shaft connected to the motor, a second sleeve splined upon said last shaft for rotation therewith, means for manually sliding the second shaft, a gear 115 carried upon the other end of said sleeve, a star wheel actuating gear also carried upon the second sleeve and in operative engagement at all times with the star wheel, means for connecting the two sleeves for unitary 120 125 movement. 130

movement, and an internal gear carried by the sign carrying member for engagement with the gear carried by the second sleeve, whereby when the clutch members are engaged intermittent motion is imparted to the sign carrying member and when the clutch members are disengaged and the internal and sleeve carried gears are engaged continuous motion is imparted to the sign carrying member.

In testimony whereof I hereunto affix my signature.

WILLIAM SHILOH WILSON.
